UNITED STATES PATENT OFFICE.

DAVID GENESE, OF BALTIMORE, MARYLAND.

TONGUE-HOLDER FOR MOUTH AND THROAT OPERATIONS.

SPECIFICATION forming part of Letters Patent No. 374,122, dated November 29, 1887.

Application filed March 8, 1887. Serial No. 230,124. (Model.)

To all whom it may concern:

Be it known that I, DAVID GENESE, a subject of the Queen of Great Britain, residing at Baltimore, in the State of Maryland, have 5 invented new and useful Improvements in Tongue-Holders for Mouth and Throat Operations, of which the following is a specification.

The administration of nitrous oxide for the 10 extraction of teeth presents several difficulties, in that the tongue swells, the jaws close spasmodically, often rendering the anaesthetic useless, and excessive hemorrhage after the first extraction renders operations difficult 15 and often causes vomiting from involuntarily swallowing blood, and, besides, in dental surgery the saliva in the mouth frequently overflows therefrom, soils ladies' dresses, and, further, the collection of such saliva is a serious 20 objection in operating on the teeth—as in filling them—and in other mouth operations.

The object of my invention is to avoid the 25 above-mentioned objections; to make operations in the mouth more convenient and clean; to siphon off the saliva from the mouth as rapidly as formed; to hold the tongue entirely away from the gum-margin, and thereby expose the teeth and roots to view, and to reflect great light over the mouth.

30 The invention also has for its objects to provide novel means for depressing and holding the tongue for the use of surgeons in spraying medicated vapors upon a patient's tonsils or surroundings of the throat to carry away the 35 fluid rapidly as it falls, and thereby permit the surgeon to use a larger quantity of the medicine undiluted by the saliva and prevent the fluid being involuntarily swallowed, at the same time giving light, preventing the tongue 40 from obstructing the use of the spray, and enabling the latter to be kept in operation a much longer time by reason of the saliva being siphoned off as rapidly as it accumulates.

To such ends my invention consists, essentially, in a tongue depressing and holding plate provided with a siphon or conduit for carrying off the saliva or fluid as rapidly as it accumulates in the mouth.

The invention also consists in a tongue holding and depressing plate provided with a siphon or conduit for carrying off the saliva or

fluid as rapidly as it accumulates in the mouth, combined with a rest which bears against the chin while the plate is pressing and holding the tongue.

The invention further consists of other features, which will be hereinafter described and claimed, reference being made to the accompanying drawings, in which—

Figure 1 is a perspective view of the device; 60 Fig. 2, a vertical central sectional view of the same; Fig. 3, a detail bottom plan view of the tongue-holding plate; Fig. 4, a transverse sectional view of the same, and Fig. 5 a view showing the device applied to the mouth of a 65 patient in connection with a bulb or syringe for starting the siphon action.

In order to enable those skilled in the art to make and use my invention, I will now describe the same in detail, referring to the drawings, where the numeral 1 indicates the tongue depressing and holding plate, which, as here shown, is approximately elliptical in shape, and on its upper surface, 2, is slightly concaved and highly polished to form a mirror for 70 lighting up the mouth. To the under side of the plate is secured a saliva or fluid conduit in the form of a tube, 3, having perforations 4 for the entrance of the saliva or fluid thereinto, this conduit connecting at the front end 75 of the plate with a main tube, 5, which extends laterally, as at 6, and then downwardly, as at 7, at right angles, or approximately so, to the plate.

I do not confine myself to the saliva-conduit 80 in the form of a tube attached to the plate, as it may be otherwise constructed and arranged. A sleeve, 8, is arranged on the main tube 5, and is provided with an attached laterally-projecting concaved rest or bearing, 9, formed to 85 fit or bear against the under side of the chin of a patient, said sleeve having a set-screw, 10, for holding it in any position to which it may be moved along the main tube 5, whereby the chin-rest and tongue-holding plate may be 90 adjusted to and from each other for applying the instrument to the patient and for adjusting the same to varying sizes of jaws. The main tube 5 may be connected by a tube, 10^a, with a hollow elastic bulb, 11, or equivalent, 95 having valves 12, whereby to draw the saliva or fluid from the mouth into the conduit 3,

tube 5, and bulb, from which it will be expelled; but I do not confine myself to this contrivance, as other means may be employed to draw out the saliva or fluid from the mouth.

5 The instrument is applied by placing the chin in the chin-rest and the plate on the tongue, and then moving these parts, the one toward the other, so as to cause the plate to depress and hold the tongue of the patient in the 10 desired position, after which the parts are held in their adjusted position by tightening up the set-screw. This constitutes a siphon tongue depressor and holder for keeping the tongue away from the instruments while operating in the mouth. The polished or mirror face of the plate illuminates the fauces or posterior portions of the throat, and by the conduit and tube all moisture secreted in the mouth during the operation is carried or 15 siphoned off, thereby avoiding the delay which arises by the necessity of the patient frequently expectorating.

The device when used in connection with my speculum, for which application for patent was made by me October 25, 1886, Serial 25 No. 217,154, will enable the dentist or surgeon to perform most of the operations in the mouth without the use of the ordinary rubber dam or similar cumbersome appliances 30 that have hitherto been necessary during dental or other operations on the oval cavity.

In operations of cleft palate the instrument is invaluable, since it prevents involuntary swallowing of blood, which nauseates the patient and impedes the surgical operation. Since the saliva and blood are siphoned off by this instrument, it permits the operator to syringe the mouth of the patient to remove clots, and a most important and valuable feature is, that 40 any root or tooth flying from the forceps or other instrument cannot be swallowed while the tongue is held, thus avoiding the danger of foreign bodies getting into the air-passages and causing death.

45 The siphon action of the device prevents overflow of saliva spoiling ladies' dresses during dental operations and economizes time in difficult operations on the lower teeth.

In treating diseases of the tonsils and 50 roundings of the throat the fluid resulting from medicated vapor sprays is carried off as rapidly as it falls, so that the surgeon can use

the spraying-instrument a greater length of time and employ a larger quantity of the medicine undiluted with the saliva. The tongue is 55 so held that it cannot interfere with the manipulation of the spraying-instrument and the fluid cannot be swallowed.

To remove the moisture from the gum-margin outside, I may mount a common T-head 60 on the bar 6, arranged to slide thereon and communicating with the air-passage. On each branch of the T-head a small rubber tube would be mounted, which would follow the general direction of the marginal tube 3, but 65 would lie outside upon the margin of the gum. The function of such tube is similar to that of the tube 3, as it serves to remove the accumulation of saliva and other secretions from the external gum-margin. 70

Having thus described my invention, what I claim is—

1. An instrument for dental and other mouth or throat operations, consisting of a tongue depressing and holding plate provided with a 75 saliva or fluid conduit, and a rest for bearing against the chin while the plate holds the tongue, substantially as described.

2. The combination, in an instrument for dental and other mouth or throat operations, 80 of a tongue depressing and holding plate, a conduit for siphoning off the saliva or fluid from the mouth, and a chin-rest, the said plate and rest being adjustable, the one toward and from the other, substantially as described. 85

3. The combination of a tongue depressing and holding plate, a perforated conduit on the underside thereof connecting with a pendent tube for carrying off the saliva or fluid from the mouth, and a chin-rest adjustably mounted 90 on said pendent tube, substantially as described.

4. The tongue-holder having its top surface concaved and polished to form a mirror, in combination with a siphoning device for carrying off the saliva or fluid from the mouth, 95 substantially as described.

In testimony whereof I affix my signature in presence of two witnesses.

D. GENESE.
